UNITED STATES PATENT OFFICE.

ALEXANDER H. MACKINNON, OF OLYMPIA, WASHINGTON.

DESIGN FOR A SEAL-PRESS CASE.

SPECIFICATION forming part of Design No. 28,799, dated June 7, 1898.

Application filed April 8, 1898. Serial No. 676,962. Term of patent 14 years.

To all whom it may concern:

Be it known that I, ALEXANDER H. MACKINNON, a citizen of the United States, residing at Olympia, in the county of Thurston and State of Washington, have invented and produced a new and original Design for a Seal-Press Case, of which the following is a specification, reference being had to the accompanying drawing, which illustrates in perspective a case showing my design in a closed condition.

The leading feature of my design consists of the seal-press case made the subject of illustration and having the shape or configuration shown.

Referring to the drawing, the seal-press case consists of the two circular dish-shaped members a and a' , the center of each member being ornamented with a circular ornament a^2 . Each circular and dish-shaped member terminates in a stem or neck b , the point of junction b' being triangular in plan and

pyramidal in side elevation. The stems or necks b are joined by an oval-shaped tube d , which is traversed by the base of a stirrup-shaped ring e , the said base e' being substantially ovate in side elevation and the body d^2 of the ring being substantially annular. The periphery of each disk member a or a' is curved, as at a^3 , to present the appearance to the eye of a series of superposed disks of decreasing diameters.

Having thus described my invention, what I claim as new, and desire to secure by Letters Patent, is—

The design for a seal-press case, substantially as shown and described.

In testimony whereof I have hereunto set my signature in the presence of two subscribing witnesses.

ALEXANDER H. MACKINNON.
